UNITED STATES PATENT OFFICE

2,148,080

WRENCH

Peter E. Matta, Chassell, Mich.

Application July 15, 1938, Serial No. 219,468

1 Claim. (Cl. 81—147)

The present invention relates to new and useful improvements in wrenches of the type including a slidable jaw and has for its primary object to provide, in a manner as hereinafter set forth a tool of this character embodying novel means whereby the movable jaw may be expeditiously adjusted as desired.

Another very important object of the invention is to provide a wrench of the aforementioned character comprising novel means for releasably securing the slidable jaw in adjusted position.

Other objects of the invention are to provide a wrench of the character described which will be comparatively simple in construction, strong, durable, highly efficient and reliable in use, compact, light in weight, attractive in appearance and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a view in side elevation of a wrench constructed in accordance with the present invention, a portion of the slidable jaw being broken away in section.

Figure 2 is a view in rear elevation of the forward portion of the tool.

Figure 3 is a cross sectional view, taken substantially on the line 3—3 of Fig. 1.

Referring now to the drawing in detail, it will be seen that the embodiment of the invention which has been illustrated comprises a bar 1 of suitable metal, said bar being preferably of substantially the cross sectional shape shown to advantage in Fig. 3 of the drawing. On the forward end of the bar 1 is a stationary jaw 2. At its other end, the bar 1 terminates in a handle 3. Ratchet teeth 4 are provided on the front of the bar 1 adjacent the handle 3. The reference numeral 5 designates a removable stop which is secured on the handle 3 at one end of the ratchet teeth 4.

Mounted for longitudinal adjustment on the bar 1 between the stop 5 and the stationary jaw 2 is a slidable inner jaw 6. The sides of the jaw 6 are recessed, as at 7. The jaw 6 has extending therethrough a bore 8 which accommodates the bar 1. In the inner end portion of the bore 8 the jaw 6 is provided with an integral tooth or lip 9 which is engageable with the ratchet teeth 4 for holding said jaw 6 in adjusted position. As illustrated to advantage in Fig. 1

of the drawing, the bore 8 is slightly tapered from end to end for permitting the jaw 6 to be rocked on the bar 1 in order that the tooth 9 may clear the ratchet teeth 4. The back of the slidable jaw 6 has formed in its inner end portion a recess 10 which is traversed by a pin 11. Journalled at an intermediate point on the pin 11 and operable in the recess 10 is a lever 12. One end of the lever 12 is engaged with the back of the bar 1. The other end portion of the lever 12 extends over a plate 13 which is integral with the jaw 6 in the recess 10. A coil spring 14 is provided between the plate 13 and the adjacent end portion of the lever 12 for pressing the other end of said lever against the bar 1. The end portion of the lever 12 which is remote from the bar 1 is provided with a recess 15 for receiving a thumb or finger.

Forwardly of the recess 10, the back of the slidable jaw 6 has formed therein an opening 16 which accommodates a comparatively heavy or stiff coil spring 17. One end of the coil spring 17 bears on the bar 1. The tension of the coil spring 17 may be regulated as desired through the medium of an adjustable plug 18 which is threaded into the opening 16.

It is thought that the operation of the tool will be readily apparent from a consideration of the foregoing. The slidable jaw 6 may be adjusted toward the stationary jaw 2 by simply pushing forwardly on said jaw 6, the spring 17 and the spring actuated lever 12 permitting the tooth 9 to ride over the ratchet teeth 4. When it is desired to adjust the jaw 6 away from the jaw 2, the lever 12 is swung away from the bar 1 against the tension of the spring 14 and said jaw 6 is rocked on the bar 1 against the tension of the spring 17 in a manner to disengage the tooth 9 from the ratchet teeth 4 or, in other words, to cause said tooth 9 to clear said ratchet teeth. The jaw 6 may then be moved toward the handle 3 to the desired position. By removing the stop 5 the slidable jaw 6 may be conveniently removed from the bar 1 by simply slipping said jaw over the handle 3. It will be noted that the recess 10 provides bifurcations 19 on the slidable jaw 6 between which the spring pressed lever 12 is operable.

It is believed that the many advantages of a wrench constructed in accordance with the present invention will be readily understood and although a preferred embodiment of the tool is as illustrated and described, it is to be understood that changes in the details of construction and

in the combination and arrangement of parts may be resorted to which will fall within the scope of the invention as claimed.

What is claimed is:—

- 5 A wrench comprising, in combination, a bar including ratchet teeth on its front, a stationary jaw on one end of said bar, a handle on the other end of the bar, an adjustable jaw slidably and rockably mounted on the bar, said adjustable 10 jaw having a tapered bore extending therethrough accommodating the bar, a tooth integral with the adjustable jaw in one end portion of the bore and engageable with the ratchet teeth for releasably securing said adjustable jaw in 15 position, a removable stop on the handle adjacent

the ratchet teeth for limiting the sliding movement of the adjustable jaw in one direction, and means on the adjustable jaw for rocking same for engaging the tooth with the ratchet teeth, said means including a lever pivotally mounted, 5 at an intermediate point on the back of the adjustable jaw on the inner end portion thereof and engageable with the back of the bar, a spring engaged with the lever for yieldingly urging same toward the bar, a comparatively heavy spring 10 mounted in the adjustable jaw forwardly of the lever and engaged with the back of the bar, and means for adjusting the tension of the second named spring.
